MOVABLE MIRROR RACK

Arnold V. Sneed, Huntsville, Ala.

Application December 30, 1948, Serial No. 150,451

Term of patent 14 years

(Cl. D14—3)

To all whom it may concern:

Be it known that I, Arnold V. Sneed, a citizen of the United States of America, residing at Huntsville, in the county of Madison and State of Alabama, have invented a new, original, and ornamental Design for a Movable Mirror Rack, of which the following is a specification, reference being had to the accompanying drawing, forming a part thereof, wherein:

Figure 1 is a perspective view of a movable mirror rack, showing my new design.

Figure 2 is a bottom plan view.

The broken line showing of the mirror and brackets in the drawing are for illustrative purposes only.

I claim:

The ornamental design for a movable mirror rack, as shown and described.

ARNOLD V. SNEED.
